UNITED STATES PATENT OFFICE.

WILLIAM E. FOWLER, SR., OF CHICAGO, ILLINOIS, ASSIGNOR TO THE FOWLER CAR COMPANY, OF CHICAGO, ILLINOIS, A CORPORATION OF ILLINOIS.

BOX-CAR.

1,078,616.

Specification of Letters Patent. Patented Nov. 18, 1913.

Application filed November 18, 1912. Serial No. 732,061.

To all whom it may concern:

Be it known that I, WILLIAM E. FOWLER, Sr., a citizen of the United States, residing at Chicago, in the county of Cook and State 5 of Illinois, have invented certain new and useful Improvements in Box-Cars, of which the following is a specification.

My invention relates to railway cars, and has particular reference to a novel single-sheathed metallic-frame box-car of the type 10 shown in my Patent No. 962,425. In construction of this type of cars, the metallic frame-work should be so designed as to provide for such disposition of the metal 15 whereby to secure maximum strength and rigidity for the weight of the material employed. Many forms have been suggested, all of which present points of advantage, but I have found in practice that a construction 20 such as shown and described herein, provides a maximum strength and rigidity for the weight of the material.

Difficulty has been experienced in providing an adequate connection between the vertical and diagonal members and the top and bottom sills. These objections, I believe, have been overcome in the present construction.

The efficiency of the design here presented 30 may be said to be secured by the general adoption of the commercial Z section throughout the frame. Such section lends itself peculiarly to this type of frame and provides the necessary rigidity to all parts 35 thereof.

My invention will be more readily understood by reference to the accompanying drawings, wherein,

Figure 1 is a side elevation of a portion 40 of a freight car constructed in accordance with my invention; Fig. 2 is a transverse vertical section of one-half of the car, the section being taken on the line 2—2 of Fig. 1; Fig. 3 is a similar view taken on line 45 3—3 of Fig. 1; Fig. 4 is an enlarged fragmentary elevation of the upper end of the car; Figs. 5 and 6 are similar views showing the upper side of the car; Fig. 7 is an enlarged detail showing the means for connecting top side-plate and top end-plate; Fig. 8 is a detail elevation of the connecting-means between the vertical, diagonal 50 and top members; Fig. 9 is a similar detail showing the connection between a single ver-

tical post and the top-plate; Fig. 10 is an 55 enlarged view of the upper end of the construction shown in Fig. 3; Fig. 11 is a continuation of the view shown in Fig. 10, the line on which the section is taken being the same as that of Fig. 10. Fig. 12 is an 60 inside fragmentary elevation showing the door-post construction; and Fig. 13 is a section on line 13—13 of Fig. 3 looking downwardly.

Referring more particularly to the drawings, it will be seen that the under-frame of the car consists of center-sills 20, body-bolster 21, cross-bearers 22, channel side-sills 23, and Z-bar floor-beams 24. Secured to such under-frame, and projecting upwardly 65 therefrom, are side-posts 25, diagonals 26, corner-angles 27 and end-posts 28. The door-posts 29 serve to outline the door-opening, and form a part of the steel skeleton. The verticals 25, diagonals 26, end 70 posts 28, and door-posts 29, are preferably 75 of commercial Z-bar construction; the corner-post 27 may be of such Z-bar construction also, although I prefer the angle-bar as shown.

The upper-plates or members to which the vertical and diagonal posts are connected, consist of Z-bar side-plate 30, which may be of commercial form, and Z-bar end-plate 31, preferably of pressed form. Carlines 85 32 tie together the top-plates 30 at points intermediate the ends thereof. The carlines and end-plates form a support for a 80 roof-structure 33.

I have now described the skeleton frame 90 in a general way; the details thereof will now be described more specifically.

The under-frame.—This under-frame is 95 of special construction in several particulars. The channel center-sills 20 are placed in their usual location. However, the body-bolsters and cross-bearers are specially constructed in order to provide a seat for the Z-bar floor-sills 24, this necessitating a change in the outline thereof and in the 100 form of connection to the side-sills. These features are covered in a co-pending application Serial No. 720,550 which resulted in Patent No. 1,062,701, dated May 27, 1913, and will not be specifically claimed herein. 105

The vertical posts.—The vertical posts 25 are preferably of Z-bar construction as described, and are securely riveted to the

5 side-sills 23 through one flange of the Z-bar, the top end of the bar terminating short of the lower edge and beneath the outwardly-projecting flange 34 of the side-plate 30. In
 10 order to secure a connection between these two members, I provide, as shown in Fig. 9, a gusset-plate 35 having right-angled flanges 36 in parallelism with the flange 34 of the plate-sill and the web 37 of the vertical 25, suitable rivets 38 serving to connect the parts rigidly together. A very rigid connection is thus provided. The gusset plates and vertical posts are suitably slotted at intervals, the side-boards 38 forming the
 15 single sheath of the car, being secured thereto by means of bolts 39, the heads of the bolts being on the interior of the car.

20 *The diagonals.*—The diagonals 26 are also of Z-bar construction, the upper ends thereof terminating just beneath the flange 34 of the top-plate and adjacent to a vertical post 25, as best shown in Fig. 8. The form of connection is similar to that shown in Fig. 9 in that a gusset-plate 40, having outstanding flanges 41, provides for a connection to the webs of the diagonal and vertical posts and to the flange 34 of the plate. Thus, the
 25 three members are rigidly secured.

25 *The end-posts.*—These posts 28 are also of Z-bar construction, and, like the posts 25, terminate beneath the flange 42 of the Z-bar end-plate 31. The form of connection to such flange is different. In this construction two angles 43 placed one on each side
 30 of the web of the post 28 and riveted thereto about against the lower edge of the flange 42 and are riveted thereto. This forms a particularly desirable and rigid connection and is found necessary by the excessive
 35 strain to be taken up by the end-posts, due to shocks in pulling and buffing and shifting of the lading longitudinally of the car.

40 It will be noted also by reference to Figs. 2 and 3, that applicant provides four end
 45 posts to each end of the car. This secures the necessary rigidity and is an advance over the custom of employing but two end posts at each end. These end posts are shown in dotted lines.

50 *The corner construction.*—The angles 27 form the means for binding the edges of the side-planks and carrying their adequate share of the load imposed thereon. The connection between such corner angles and
 55 the top end and side-plates is in the form of plates 44 having a projecting-flange 45. The body of the plate is riveted to the angle, whereas the flange is riveted to the bottom-flange 42 of the end-plate and the bottom-flange 34 of the side-plate. Preferably, I
 60 provide separate plates 44, one for the end and one for the side, although a single plate might be used if desired. The connection between the flanges of the plates, as well as
 65 the connection between the ends of the side

70 and end-plates is best shown in Fig. 7. The connection is formed by means of a bent plate 46 having rivet connection through both the flanges 34, 45 and 42, 45, and rivet connection to the webs of the plates 30 and 31.

75 *The door construction.*—This construction as shown in Figs. 10 to 13, also includes Z-bars as elements. The posts 29 are of Z-bar construction and are connected to the side-plate in the manner shown in Fig. 9. Riveted to one of the door-posts 29 is a plate 47 which forms a stop for the closed sliding-door. As a threshold I provide the angle-bar 48 riveted to the web of the side-sill 23. One of the rivets 49 assisting in securing this angle to the side-sill also secures an angle 50 to the side-sill, this angle having a connection to the web of the cross-beam 22. This is best shown in Fig. 3. A Z-bar 51 secured to the lower margin of the car-door 52, co-operating with guides 53 prevents the outward swinging of the door. The top construction of the door as shown in Fig. 10, is as follows: To the outwardly-projecting flange 34 of the side-plate 30 is attached a plate 54 having a downturned marginal flange 55, the upper marginal edge of the door being seated behind this downturned flange 55, a wearing plate 56 engaging therewith. The plate 54 forms a track on which the rollers of door-hangers 57 may ride.

80 The car ladders on the ends and sides of the car are formed by securing the ladder rungs to the vertical members, as best shown in Figs. 4 to 6 inclusive. On the ends the rungs are attached to the angle corner-post 27 and to the end-post 28. On the side the rungs are attached to the corner-post angle 105 27 and to an angle 58 extending vertically of the car between the side-sills and side-plates, being secured to the side-plate by means of angles 59.

85 It is obvious that many modifications might be made in the constructions here shown, and such modifications as are within the scope of my claims I consider within the spirit of my invention.

90 I claim:

1. In a railway-car, the combination of a steel-skeleton composed of under-framing, side-posts, end and side plates, corner-posts, said end and side-plates being of Z-bar construction, means for attaching the projecting flanges of said end and side plates at their ends, a single sheathing applied interiorly of said steel-skeleton, and a roof-structure, substantially as described.

115 2. In a railway-car, the combination of a steel-skeleton composed of under-framing, verticals, diagonals, end-posts, end and side-plates, all said verticals, diagonals and plates being of Z-bar construction, a flange of the Z-bar side and end plates projecting out- 120

125

130

135

wardly in such manner as to provide means for attachment to said verticals, a roof-structure, and a single interior sheathing, substantially as described.

3. In a railway-car, the combination of a steel-skeleton composed of under-framing, verticals, diagonals, end-posts, end and side-plates, the upper ends of all said verticals, diagonals, and end-posts terminating below the lower edge of said end and side-plates, slotted connecting-plates therefor, a single interior sheathing, bolts passed through said sheathing and the slots in said plates whereby relative movement between said sheathing and plates is permitted, and a roof-structure, substantially as described.

4. In a railway-car, the combination of a steel-skeleton composed of under-framing, Z-bar side and end-posts, Z-bar top-plates, the upper edge of said posts terminating short of the lower edge of said plates, angle-plates connecting said posts and sills, a roof-structure, and a single interior sheathing, substantially as described.

5. In a railway-car, the combination of a steel-skeleton composed of under-framing, said under-framing including angular side-sills, Z-bar vertical posts secured to said side-sills, Z-bar top-plates, the upper ends of said posts terminating beneath the outwardly-projecting flange of said plates, connecting-means between said posts and plates,

a roof-structure, and a single interior sheathing, substantially as described.

6. In a railway-car, the combination of a skeleton - frame including under - framing, Z-bar vertical posts, Z-bar diagonals, Z-bar top-plates, said vertical and diagonal posts terminating beneath the outwardly-projecting flange of said plates, means for connecting together said vertical and diagonal posts and plates, and a roof-structure, substantially as described.

7. In a railway-car, the combination of a steel-skeleton including angular side-sills, slotted Z-bar vertical posts, Z-bar end and side-plates, means for connecting the projecting flanges of said end and side plates, suitable connecting means between said vertical members and said plates, a single interior sheathing, fastening bolts passed through said sheathing and the slots in said Z-bar, and a roof-structure, substantially as described.

8. In a railway-car, the combination of a steel - skeleton including angular vertical members, Z-bar end- and side-plates, and a plate connecting the webs and outwardly projecting flanges of said Z-bar end and side plates, substantially as described.
